UNITED STATES PATENT OFFICE.

CLYDE S. PELTON, OF CLEVELAND HEIGHTS, OHIO, ASSIGNOR TO THE PERFECTION
HEATER & MFG. COMPANY, OF CLEVELAND, OHIO, A CORPORATION OF OHIO.

VALVE CONTROL FOR MOTOR-CAR HEATERS.

Application filed February 25, 1922. Serial No. 539,217.

To all whom it may concern:

Be it known that I, CLYDE S. PELTON, a citizen of the United States, residing at Cleveland Heights, in the county of Cuyahoga and State of Ohio, have invented a certain new and useful Improvement in Valve Controls for Motor-Car Heaters, of which the following is a full, clear, and exact description, reference being had to the accompanying drawings.

This invention relates to heaters for motor-propelled vehicles and has for its objects the provision of a simple and convenient fitting for enabling the control of the heater from any convenient part of the vehicle; the provision of a control-fitting which shall be interchangeably usable with all types of cars regardless of the relative position of the valve and fitting; the provision of a fitting for this purpose which shall enable a maximum amount of force to be applied to the valve when the same is at or near its closed position, for the purpose of opening or closing it against the carbon deposits usually encountered in connection with such installations; while further objects and advantages of the invention will become apparent as the description proceeds.

In the drawings accompanying and forming a part of the present application wherein I have illustrated one embodiment of said invention, Fig. 1 illustrates a part of an automobile having a heater attached to the exhaust pipe and provided with my improved valve control; Fig. 2 is an enlarged side elevation partly in section of said valve control; and Fig. 3 is a view taken at right angles to Fig. 2.

Describing the parts by reference characters, 1 represents the floor of an automobile, 2 the exhaust pipe, 3 a heater, and 4 a flexible conduit leading to the heater, the latter being attached to the exhaust pipe by means of the valve-fitting 5 clamped to one side thereof and having therein a valve member 6 adapted to deflect more or less of the exhaust gases into the heater. In its preferred form the valve member 6 is carried by a rotatable spindle 7 provided with a lever 8 and a closing spring 9 to which is attached the operating rod 10.

The opposite end of this rod is connected to a suitable fitting secured at such place in the floor of the car as may be necessitated by the car construction or indicated by the de-

sire of the owner. In its preferred construction this device comprises an apertured floor flange 12 having spaced side walls 13 and end walls 14 surrounding the aperture, the bottom of the flange being formed at one side of the aperture with a bracket 16 to which is pivoted the segmental plate 17 whose periphery is formed with spaced apertures 18. Articulated to this plate as by a pin entering one of its apertures is an upwardly projecting handle 20, which traverses the aperture and is provided at its upper end with a cross-piece 21 adapted to be engaged by the hand. One side of this handle is formed with spaced notches 22 adapted to engage the adjacent wall of the aperture which is preferably formed with a deflected portion 23 to cooperate therewith. The opposite side of the handle is provided with a projecting portion 24 and the casing 75 is provided with a suitable abutment such as the rivet 25 so located as to engage said projecting portion and force the topmost notch into engagement with the detent portion 23, thus limiting the downward movement of 80 the handle.

The end of the rod 10 is formed with a transverse pivot portion 30 adapted to be inserted in one of the holes 18 where it is suitably held as by a cotter pin 31. The angular extent of the sector being preferably at least 90°, the same forms a sort of universal bell-crank lever enabling the operation of the valve by this handle in any relative position of the valve and sector 90 likely to be found in an automobile. In the present embodiment I have shown this rod as engaged with the third aperture, thereby causing the same to swing a substantially equal angle to each side of the midpoint. 95 The valve lever 8 is also secured to the rock shaft so as to provide the best possible linkage connection. This ordinarily requires that the rod be approximately perpendicular to the lever when the valve is half open; and the rod is connected to such a point on the segment plate as to remain as nearly parallel to its mean portion as possible through its entire range of travel. It is obvious that these angles will vary with differences in height between the exhaust pipe and floor and differences in horizontal distance between the valve and control fitting. This improved fitting constitutes, in effect, a universal bell-crank lever usable in all 105 110

relations from direct vertical alignment to a full horizontal throw.

The flange 12 is shown as applied to the bottom of the car-floor, the walls 13-14 being received in a suitable hole 35, covered by a slotted plate 36 to which the flange is bolted. In the present embodiment I have shown a floor-type heater located in the rear compartment of the automobile, the control device being located in the forward compartment just ahead of the heel board 32. The closing spring 9 is so related to the parts as to hold the notches 22 tightly engaged. In case the handle is released the spring closes the valve with a forcible snap, dislodging any carbon that may have accumulated, the cam projection 24 serving to throw the handle so as to engage the last notch at the instant the valve is closed. In this way the tension of the spring 9 is utilized to take up any lost motion in the connections and prevent rattling. To this end it is desirable to employ a rod 10 of such length as to effect this engagement of the notch just prior to the contact of the valve with its seat or with any stop carried by the valve itself. It will be understood however that I do not limit myself to the employment of any particular type of heater or valve or location of control device, or any other feature of design, construction or arrangement except as specifically recited in my claims.

Having thus described my invention what I claim is:

1. A fitting for the purpose described, comprising a slotted plate adapted to be attached to a floor, a bracket carried by one side of said plate alongside said slot and formed at a point removed from the plate with an extension beyond one end of said

slot, a lever pivoted to said extension, an operating handle pivoted to said lever and projecting through said slot, and a hand grip carried by said handle.

45

2. A fitting for the purpose described, comprising an apertured plate adapted to be attached to a floor, and formed on one side with walls at opposite sides of the said aperture and upon the other side with a bracket along the side of such aperture, the end of said bracket being extended to a point beyond one end of said aperture, a bell-crank lever pivoted to the end of said bracket, an operating handle pivoted to said bell-crank lever and projecting through the aperture, said bell-crank also being apertured for the reception of an operated rod and the edge of said handle being notched for engagement with one of said walls.

60

3. A fitting for the purpose described, comprising an apertured floor flange having a bracket at one side and displaced from the aperture of swinging plate pivoted to said bracket upon an axis which is substantially parallel to the plane of said flange and having near its margin a series of spaced apertures, an operating handle articulated to said plate and projecting through said flange aperture, one edge of said handle being notched for engagement with the wall of said aperture and the opposite edge having a projection, an abutment carried by said flange adapted to engage said projection when the uppermost notch comes opposite said wall, and a rigid rod having a transverse pivot-portion adapted to enter and be secured in one of the marginal apertures of said plate.

65

In testimony whereof, I hereunto affix my signature.

CLYDE S. PELTON.
